(57) **CLAIM**

We claim the ornamental design for a double walled metallic bowl, as shown and described.

DESCRIPTION

FIG. 1 is a top perspective view of a double walled metallic bowl according to our new design;

FIG. 2 is a left end elevation view thereof, the right end elevation view being identical;

FIG. 3 is a top plan view thereof;

FIG. 4 is front elevation view thereof, the rear elevation view being identical;

FIG. 5 is a bottom plan view thereof;
